UNITED STATES PATENT OFFICE.

JOHN A. PETRI, OF BROOKLYN, ASSIGNOR TO KOCH SONS & COMPANY,
OF NEW YORK, N. Y.

DESIGN FOR A BOOK OR ALBUM.

SPECIFICATION forming part of Design No. 19,528, dated December 24, 1889.

Application filed September 12, 1889. Serial No. 323,777. Term of patent 7 years.

To all whom it may concern:

Be it known that I, JOHN A. PETRI, a citizen of the United States, residing in Brooklyn, in the county of Kings and State of New York, have invented and produced a new and original Design for a Book or Album, of which the following is a specification, reference being had to the accompanying drawings, forming part thereof, in which—

Figure 1 represents two album-leaves as opened out, and Fig. 2 is a section of the same.

The leading feature of the design consists of a book or album the outline or configuration of the leaves of which is hexagonal.

The front edge *e* and back edge *f* of the leaf are parallel, or nearly so, and there are two lines *g h* bounding the edge of the leaf at the top and two lines *i k* bounding the edge of the leaf at the bottom, and the angles between the respective lines are obtuse, so as to form a hexagonal figure. The leading hex-

agonal feature of my design is the same when the back and front edges are nearer to each other than they would be in an equal-sided hexagon; or one-half of the hexagon may be equal-sided, as indicated by the dotted line *e'* and the dotted prolongations of the lines *h* and *k*. The cover is usually the same shape, but larger. The shapes and positions of the openings for the photographic pictures may be varied without changing my design, or such openings may be omitted.

What I claim is—

In a design for a book, the design of the leaves, substantially as herein shown and described.

Signed by me this 9th day of September, 1889.

JOHN A. PETRI.
